UNITED STATES PATENT OFFICE

HENRY STEPHENS, OF CLEVELAND, OHIO, ASSIGNOR TO THE P & M COMPANY, OF CHICAGO, ILLINOIS, A CORPORATION OF ILLINOIS

RAIL JOINT ANCHOR

Application filed February 27, 1931. Serial No. 518,752.

This invention relates to rail anchor devices adapted to clamp a portion of a railroad rail and engage a stationary part of the roadbed to resist longitudinal creeping movement of the rail.

The principal object of the invention is to provide a rail anchor of simple and inexpensive construction which can be applied to a rail at the joints and which when in its applied position will have an interlocking engagement with one of the splice bars of the rail joint. Specifically, the invention includes a device having upper and lower jaws adapted to be driven into clamping engagement with the lateral flange of an angle splice bar and the bottom surface of a rail base, the anchor having a portion which by reason of the resiliency of the anchor springs over and interlocks with an edge portion of said splice bar so as to maintain the anchor device in its applied position on the rail.

A further and more specific object of the invention is to provide a rail anchor of the above construction which engages one side only of a rail and which preferably, though not necessarily, is driven transversely of the rail to its applied position.

Other objects of the invention will be apparent from the detailed description of the construction and operation of the specific embodiments shown in the accompanying drawings, wherein:

Fig. 1 is a side view of a rail joint and showing one of my improved rail anchors applied to the rail in a position to bear against a cross tie.

Fig. 2 is a cross section taken on line 2—2 of Fig. 1 illustrating the manner in which the rail anchor device grips the base portion of a rail and interlocks with the rail joint splice bar.

Fig. 3 is a view in perspective of the anchor device shown in Figs. 1 and 2.

Fig. 4 is a view similar to Fig. 2 showing a rail anchor in its applied position, the rail anchor of this figure being formed from a bar bent to the configuration shown.

Fig. 5 is a view in perspective of the anchor device shown in Fig. 4.

Fig. 6 illustrates another embodiment of

the invention in which the anchor device has an interlocking engagement both with the rail joint splice bar and with the longitudinal edge of the rail base at the opposite side of the rail, and

Fig. 7 is a view in perspective of the anchor device shown in Fig. 6.

Referring first to Figs. 1 to 3 inclusive of the drawings 10—10a designates adjacent ends of railroad rails which are clamped together by means of splice bars 11—11a and clamping bolts 12. The splice bars may be of any desired length. Ordinarily these members are of such length as to extend over substantially three cross ties. The splice bars illustrated in the drawings are of a general angular construction having a lateral flange which seats upon the inclined upper surface 14 of a rail base flange. Preferably the lateral flanges 15 of the angle bars are formed with an inclined upper surface 16 and terminate with downturned edges 17 which in the normal position of the angle bar are spaced a short distance from the adjacent edges 18—18 of the rail base flanges.

The rail anchor illustrated in these figures is preferably formed from flat metal stock recessed to provide an upper jaw 19 and a lower jaw 20 which together embrace the lateral flange of one splice bar and the adjacent marginal portion of a rail base flange. The jaws 19 and 20 are resilient and are normally spread apart in applying the anchor to its operative position so that, when the anchor is in its applied position, the said jaws grip the flange 15 of the splice bar and the bottom surface of the rail base with spring pressure.

The bearing surface of the upper jaw 19 grips the inclined upper surface 16 of the angle splice bar and the lower jaw engages both the lower edge 21 of the splice bar and the bottom surface 22 of the base of the rail 10. The lower edge of the said splice bar serves as a fulcrum bearing against which an upward turning pressure is exerted to force the end portion of the lower jaw 20 into gripping contact with the rail base.

The lower jaw 20 is also formed with a raised shoulder portion 23 which, in the applied position of the anchor, engages

the inner edge of the downturned portion 17 of the angle bar and serves to lock the anchor firmly in its applied position. The shoulder 23 may be of any suitable height and configuration. Preferably it is curved to provide a cam surface 24 which will move beneath the lower edge 21 of the angle bar and snap, by the resiliency of the anchor, into the space between the down-turned portion 17 of the splice bar and the adjacent edge 18 of the rail base flange. The anchor device may be applied to either side of the rail joint in a position whereby the lower jaw 20 of the anchor will abut against a vertical face of a cross tie 13. The angular arrangement of the anchor as shown in Fig. 2 makes it possible to provide a relatively deep tie abutting portion, that is to say a tie abutting portion which engages the tie at a substantial distance below the bottom surface of the rail base, without requiring the use of additional metal.

In applying the anchor to a rail joint structure, the upper jaw 19 is hooked over the marginal portion of the angle bar and the anchor is driven transversely of the rail until the shoulder 23 snaps over the inner edge of the down-turned portion 17 of the angle bar. In this position of the anchor the jaws 19 and 20 are spread apart and consequently grip the upper surface of the angle bar and the bottom surface of the rail base respectively.

In Figs. 4 and 5 of the drawings a modified form of anchor is illustrated in connection with a rail joint structure of the same construction as shown in Figs. 1 and 2. This modified form of rail anchor is preferably made from a relatively heavy bar 40 of metal which is bent at one end to a hook shaped configuration to provide a short arm or jaw 25 and a long arm 26. The short arm or jaw 25 is formed at its end with a bearing 27 adapted to bear on the inclined upper surface 16 of the angle splice bar 11 at a point located inwardly from the outer margin of the angle bar. The long arm 26 includes a portion 28 which functions as a lower jaw for gripping the under surface 50 of the downturned portion 17 of the angle splice bar and a tail portion 29 which bears against the bottom of the rail base, preferably at the middle of said base. The said tail portion is formed with a flat surface 55 so as to increase the frictional engagement of the said tail portion with the bottom surface of the rail when the anchor is in its applied position. The portion of the arm 26 intermediate the bearing 30 and the jaw portion 28 is bowed downwardly relative to the bottom surface of the rail base so as to provide a tie abutment which engages the tie at a substantial distance below the bottom surface of the rail base. The portion of the arm adjacent the jaw portion

28 is formed with a locking shoulder 31 which normally snaps over the lower inner edge of the portion 17 of the angle splice bar when the anchor is moved to its applied position. The jaw 25 when free of the rail assumes the position indicated in dotted lines in Fig. 4, consequently in applying the anchor to the rail it is necessary to spread the upper and lower arms apart. The tendency which the arms 25 and 26 have to resume the position from which they are sprung exerts a tight spring gripping action on the top surface of the splice bar, the lower surface of the portion 17 of said bar and the bottom surface of the rail base. This anchor is applied to its operative position in the same manner as that indicated in connection with the form of invention shown in Figs. 1 to 3 inclusive, the bottom surface of the downturned portion 17 serving as a fulcrum bearing which by reason of the downward pressure of the surface 27 on the inclined surface of the angle splice bar forces the bearing 30 at the tail of the device up against the bottom surface of the rail base. The curvature 32 of the arm adjacent shoulder 31 serves as a cam to spread the arms 25 and 26 apart when the inner end of the arm 25 is driven upwardly on the inclined surface 16 of the splice bar 11.

In Figs. 6 and 7 another modified construction is shown in which the anchor device has an interlocking engagement with the lower inner edge of the downturned portion 17 of the angle splice bar 11 and also has a locking engagement with the vertical edge portion of the rail base at the opposite side of the rail. This modified construction is illustrated herein as being made from flat plate stock of substantially the same thickness as shown in Figs. 2 and 3. It will be obvious, however, that this form of anchor can be made by bending a metal bar such as shown in Fig. 5 if it is so desired. The anchor device shown in Figs. 6 and 7 consists of an under-rail portion 33 formed to engage the bottom surface of the rail base adjacent opposite edges thereof. One end of the under-rail portion is formed with an upper jaw 34 which engages the inclined upper surface 16 of the angle splice bar 11 and is formed also with a lower jaw 35 which bears against the bottom surface of the downturned portion 17 of the splice bar. A locking shoulder 36 is formed adjacent the bearing surface of the lower jaw 35 in a position to snap over the lower inner edge of the portion 17 of the splice bar when the anchor is driven to its applied position on the rail. The said shoulder 36 serves to interlock the anchor with the splice bar. The other end of the under-rail portion 33 is provided with a shoulder 37 which in the applied position of the anchor interlocks with the edge of the rail base at the opposite side of the rail, the

said shoulder 37 projecting into the space between the edge of the rail base and the down-turned portion 17a of the angle splice bar 11a. The under-rail portion 33 of the anchor is also preferably formed with a downwardly projecting portion 38 for increasing the depth of the tie abutting face of the anchor. The portion 38 may be formed to extend any suitable distance below the bottom 10 surface of the rail base.

This form of anchor is applied to its operative position by driving it transversely of the rail in the same manner as described in connection with the embodiments shown in 15 Figs. 2 and 4, until the shoulders 36 and 37 snap into their interlocking engagement with the splice bar and lower corner portion of the rail base respectively. The resilience of the jaw end 34 of the anchor exerts an upward 20 force on the opposite end of the anchor to hold the shoulder 37 in its locking position.

While the invention is illustrated herein in three specific embodiments in which the upper and lower jaws have certain proportions, 25 it will be obvious that the proportions shown can be varied without departure from the scope of this invention and that it should be understood that the claims hereto appended should not be limited except insofar as limitations are expressed therein or imposed by the prior art.

I claim:

1. A rail anchor for application to a rail joint structure and comprising a clamp member provided with means for gripping engagement with a rail joint splice bar, means providing an interlock between the clamp and a portion of the splice bar, and means for abutting against a stationary part of the 40 road bed.

2. A rail anchor for application to a rail joint structure and comprising a clamp member provided with means for gripping engagement with the rail joint splice bar, means on the clamp providing an interlock between the clamp and a portion of the splice bar, and means for abutting against a stationary part of the road bed.

3. A rail anchor for application to a rail joint structure and comprising a clamp member provided with means for gripping engagement with a rail joint splice bar and the base portion of the rail, a shoulder on the clamp which, in the applied position of the 55 clamp, interlocks with a portion of the splice bar to maintain the clamp in its applied position, and means for abutting against a stationary part of the road bed.

4. A rail anchor for application to a rail joint structure and comprising a clamp member having upper and lower jaws adapted to grip a rail joint splice bar and a portion of the rail base respectively; a portion of said lower jaw being formed to interlock with an edge portion of said splice bar to main-

tain the clamp in its rail gripping position.

5. A rail anchor for application to a rail joint structure and comprising a clamp member having upper and lower jaws adapted to grip a rail joint splice bar and a portion of the rail base respectively; said lower jaw being provided with a shoulder which, in the applied position of the clamp, interlocks with an edge portion of said splice bar to maintain the clamp in its applied position.

6. A rail anchor for application to a rail joint structure and comprising a plate member recessed to provide upper and lower jaws which embrace and grip a portion of a rail joint splice bar and one flange of the rail base respectively, the said lower jaw being formed with a shoulder for locking engagement with said splice bar.

7. A rail anchor for application to a rail joint structure and comprising a member formed with upper and lower jaws adapted to be driven into gripping engagement with the upper and lower surfaces of a rail joint splice bar; said lower jaw being formed with a portion for engaging the bottom surface of the rail base.

8. A rail anchor for application to a rail joint structure and comprising a member formed with upper and lower jaws adapted to be driven into gripping engagement with the upper and lower surfaces of a rail joint splice bar; said lower jaw being formed with a portion for locking engagement with said splice bar and with a portion for engaging the bottom surface of the rail base.

9. A rail anchor for application to a rail joint structure and comprising a bar bent to form at one end upper and lower jaws adapted to be driven into gripping engagement with the upper and lower surfaces of a rail joint splice bar; said lower jaw being formed with a portion extending inwardly from its said engagement with said splice bar and adapted to bear against the bottom surface of the rail base.

10. A rail anchor for application to a rail joint structure and comprising a bar of resilient metal bent to form at one end thereof upper and lower jaws adapted to be driven into gripping engagement with the upper and lower surfaces of a rail joint splice bar; the said lower jaw being formed with a downwardly bowed extension providing a tail portion which, in the applied position of the anchor, bears against the bottom of the rail base and also abuts against a vertical face of a cross tie.

11. A rail anchor for application to a rail joint structure and comprising a bar bent to form at one end of the anchor upper and lower jaws which embrace a portion of a rail joint splice bar, the lower jaw providing a fulcrum bearing for engaging the bottom of said splice bar and the upper jaw

bearing on an inclined surface of said splice bar whereby inward movement of the anchor on the inclined surface of the splice bar rocks the anchor about said fulcrum bearing; the said lower jaw including a portion which bears against the bottom surface of the rail when the anchor is forced to its applied position.

12. A rail anchor for application to a rail joint structure and comprising a bar bent to form at one end of the anchor upper and lower jaws which embrace a portion of a rail joint splice bar, the lower jaw providing a fulcrum bearing for engaging the bottom of said splice bar and the upper jaw bearing on an inclined surface of said splice bar, whereby inward movement of the anchor on the inclined surface of the splice bar rocks the anchor about said fulcrum bearing; the said lower jaw being formed with a portion for locking engagement with said splice bar and with a downwardly bowed portion which bears at its extremity against the bottom surface of the rail base.

13. A rail anchor for application to a rail joint structure and comprising a bar which extends across and beneath the base portion of the rail and formed at one end with a shoulder for locking engagement with one edge of the rail base and formed at the other end with upper and lower jaws for engaging the top and bottom surfaces of a rail joint splice bar, the said lower jaw being formed with means adapted to move into interlocking engagement with the said splice bar when the anchor is forced to its applied position.

14. A rail anchor for application to a rail joint structure and comprising an under-rail portion formed at one end with upper and lower jaws adapted to be driven into gripping engagement with the top and bottom surfaces of a rail joint splice bar and formed at the other end with a shoulder which, in the applied position of the anchor engages over the lower corner portion of the base flange of the rail at the opposite side of the rail.

15. A rail anchor for application to a rail joint structure and comprising a bar having a downwardly bowed underrail portion adapted to bear against a cross tie and formed at one end with a shoulder for locking engagement with the lower corner portion of a base flange at one side of the rail base and formed at the other end with an inwardly projecting jaw for gripping engagement with a rail joint splice bar whereby the said anchor device is maintained on the rail by a clamping action exerted on the said splice bar and rail base respectively.

16. The combination with a base portion of a railroad rail and an angle splice bar for joining said rail with another, said splice bar being formed at its outer edge with a downturned portion, of a rail anchor comprising a clamp formed with an upper jaw for engag-

ing over the marginal portion of said splice bar, a lower jaw for engaging the bottom surface of said rail base, and means on the lower jaw which, in the applied position of the clamp, interlocks with a portion of said splice bar to maintain the anchor device in its applied position.

17. The combination with a base portion of a railroad rail and an angle splice bar for joining said rail with another, said splice bar being formed at its outer edge with a downturned portion normally spaced outwardly from the edge of the base flange of the rail, of a rail anchor device for application to one side only of said rail joint structure and comprising a clamp member formed with upper and lower jaws which embrace the marginal portion of said angle bar and a portion of the adjacent base flange of the rail, and means on the clamp adapted to project into the space between the said downturned portion of the splice bar and the adjacent edge of the rail base to lock the anchor device in its applied position.

18. The combination with a base portion of a railroad rail and a splice bar for joining said rail with another, the said splice bar being formed to project beyond the edge of the rail base and having a shoulder located inwardly from the outer edge of said bar, of a rail anchor provided with means adapted to be forced transversely of the rail into gripping engagement with a top and a bottom surface of said splice bar and provided with a locking shoulder adapted to spring into locking engagement with the said shoulder of the splice bar when the anchor is forced to its operative position.

19. The combination with the base portion of a railroad rail and a splice bar for joining said rail with another, the said splice bar being formed to project beyond one edge of the rail base and is formed with a shoulder located inwardly from the outer edge of said bar, of a rail anchor comprising a spring metal bar bent to form a short arm for gripping engagement with the top surface of said splice bar and a long arm having an interlocking engagement with the shoulder of the said splice bar and bowed downwardly beneath the rail base and bearing at its extremity against the bottom surface of the rail base.

HENRY STEPHENS.
